CLAIM

The ornamental design for a shoe, as shown and described.

DESCRIPTION

FIG. 1 is a top, right, front perspective view of an ornamental design for a shoe;

FIG. 2 is a right side elevational view of the shoe of FIG. 1; and,

FIG. 3 is a top, right, rear perspective view of the shoe of FIG. 1.

The dash-dash-dash broken lines are included for the purpose of illustrating portions of the shoe that form no part of the claimed design. The dash-dot-dash broken lines depict boundary lines and form no part of the claimed design. The oblique shade lines indicate a transparent or translucent surface or material.
